UNITED STATES PATENT OFFICE.

RICHARD MACK, OF NEU-TEMPELHOF, NEAR BERLIN, GERMANY.

ELECTRIC TRANSFORMER AND WELDING, SMELTING, AND LIKE APPARATUS.

1,199,092.

Specification of Letters Patent. Patented Sept. 26, 1916.

Application filed September 12, 1913. Serial No. 789,500.

To all whom it may concern:

Be it known that I, RICHARD MACK, a subject of the Emperor of Germany, residing at Dreibundstrasse No. 45, Neu-Tempelhof, 5 near Berlin, Germany, have invented certain new and useful Improvements in or Relating to Electric Transformers and Welding, Smelting, and like Apparatus, of which the following is a specification.

10 The object of my invention is to provide a simple, cheap and efficient single phase, low tension electric transformer.

To this, and other subsidiary ends, my invention consists in the combination of elements hereinafter more particularly described and definitely pointed out in the claims.

In the drawings, Figure 1, is a central sectional view of a transformer embodying the features of my invention, Figs. 2 and 3, are like views showing modifications of said invention, Fig. 4, is a like view of an apparatus as it would appear when adapted for point-welding purposes, Fig. 5, is a like sectional view showing the device as it would appear when adapted for butt-welding, and Fig. 6, is a cross sectional view of Fig. 5.

Corresponding reference letters in the different figures indicate like parts.

30 In Fig. 1 *a* and *b* designate the secondary coil formed as a casing consisting of a receptacle and cover *b*; *c* is the laminated core and *d* the primary coil or winding.

In Fig. 2 *e* is a central shaft passing through the center of the transformer which can be rotated and serves as a rotating electrode. *f* is a belt pulley for driving the shaft *e*.

In Fig. 3 *g* is a melting pot of refractory, but electrically conducting material and *h* designates the mass to be melted.

Fig. 1 shows the complete transformer and in Figs. 2 and 3 the primary coil and the laminated core are omitted. The path 45 of the welding current in the secondary coil is indicated in Fig. 1 by the broken line. The poles of the secondary conductor, in the embodiment of the invention illustrated in Fig. 1, are indicated by the plus and minus signs at which place the welding apparatus can be connected.

In Fig. 2 *e* and *b* are the poles or elec-

trodes of the secondary conductor. In this construction, the central part *a*, is formed to constitute a bearing for the rotary electrode *e*, which is adapted to be driven from the belt pulley *f*. The advantage of this, among other things, is that superfluous connections are eliminated and the length of the secondary conductor may be reduced to 60 the utmost limit. In practice it frequently happens that for the continuous welding of certain objects, or welding which is intermittent or continuous, a rotary electrode is required, and in such a case the arrangement of the secondary conductor is of great 65 importance because by this means the sum of the resistances in the secondary conductor circuit is reduced to the minimum owing to the absence of joints and intermediate elements. The shaft *e* is wholly or partially 70 an electrical conductor and can be driven by the belt pulley *f* or other appropriate transmission means.

Fig. 3 illustrates the invention in its simplest form as a melting furnace, as the secondary circuit is closed by the material of the melting pot which is of higher resistance than the object to be melted, as in Figs. 1 and 2. It will be understood that by providing a suitable space between the melting pot and the primary winding, and by air or water cooling, the primary winding can be adequately protected from the smelting heat. Here also the melting pot can be provided in the usual manner with a pouring 80 spout and the casing with trunnions so that the whole can be rotated for pouring the molten mass.

If desired, the complete transformer can 90 be arranged upon an under frame on legs or the like, in order to facilitate its manipulation.

In the drawing, the apparatus illustrated is of circular form, but this is not indispensable or necessarily advantageous. Cases 95 may arise in which the secondary winding *a*, the laminated core *c* and the primary winding *d* must be given a rectangular form. The outer wall of the secondary coil can also 100 advantageously be provided with vents of appropriate size for air cooling as shown at *a'* Fig. 3.

Figs. 4 and 5 and 6 illustrate practical

constructional forms of the transformer hereinbefore described in connection with a point and a butt-joint welding apparatus.

In the several figures, *a* and *b*, as before, 5 represent the secondary winding, which, at the same time, forms a casing; *c* is the laminated core and *d* the primary winding; *e* is the lower electrode arm, which, in point welding machines, is usually stationary, and 10 *f* is the upper electrode arm rotatable about the shaft *f'* in the bearing *f''*.

i designates insulating material serving to insulate the upper electric arm *f* from the cover forming part of the secondary 15 winding *b*.

k is a flexible conductor between *f* and *a* and consists of a plurality of bent strips of conducting material with the object of enabling the arm *f* to be easily displaced 20 while at the same time affording a good metallic connection.

l is the under frame of the transformer which in the present case consists of two standards connected together near the floor 25 by a tie rod *m*.

n is a pedal for actuating the apparatus connected with the lever electrode *f* by a rod *o*.

p is a pivot fixed to the lever *f* engaging 30 a slot *q* in the rod *o*.

r and *s* are members carrying the primary contacts, etc., which are insulated one from the other, and from the said members so that they are not in metallic contact. While 35 the member *r* is freely movable in a vertical direction on the rod *o* the member *s* is secured to the rod *o* by a pin so that the member *s* is able to rock on the rod *o*.

u is a spring arranged between members 40 *r* and *s*, in order, on the one hand to hold the contact pieces *t* at a suitable distance apart when the apparatus is inoperative, and on the other hand, to press the welding electrodes *v* together. It is desirable that 45 they should be brought together before closing the electric circuit therewith. When the operator presses his foot upon the treadle the first action is to cause them to contact, after which, a further pressure acts 50 to compress the spring until the electric circuit is closed.

In Fig. 5 *w* designates clamps for holding the articles to be welded such as bars *x* for example. These clamps *w* also form the 55 poles of the secondary coil. *y* is a threaded spindle mounted on a fixed portion of the casing, and provided with a hand wheel so that by means of a projection on the upper portion or cover *b* which is here formed as 60 a support (Figs. 5 and 6) the latter can be shifted for example when the heated work is to be moved into the welding position. *z* are guide bars for guiding the cover *b* (Fig. 6),

In the embodiment of the invention illustrated in Fig. 4 the complete transformer is combined with a point welding apparatus. When the pedal *n* is depressed, the primary circuit is closed through the contacts *t* when the ends marked plus and minus are 70 connected with single phase alternating current and simultaneously pressure is produced between the electrode points *v* and between the material located between them, that is to be welded. The path of the current is indicated by the arrows. 75

The position of the arm *e* on the wall of the casing is of great importance. At this place the wall of the casing is provided with slots similar to the slots used in connecting 80 a machine tool to a bed plate for the purpose of enabling the arm *e* to be adjusted horizontally and vertically in a convenient manner. The under frame *l* is fixed directly to the bottom of the casing. 85

The opening of the electrodes *v* takes place automatically under the influence of gravity after the pedal has been released. A weight or spring can, however, be employed for this purpose if desired. 90

If necessary the welding apparatus can also be driven by a motor or the like; in other words the examples here given are illustrated diagrammatically only. 95

Figs. 5 and 6 illustrate a constructional 95 form of the machine combined with a butt welding apparatus. Here also the path of the secondary current is indicated by the arrows. Cases may arise in which a long form of casing is desirable, but this would 100 give rise to unfavorable dimensions as regards the constructions hitherto adopted for the laminated transformer coils. Accordingly instead of a single central conductor *a*, two or more such conductors and an 105 equal number of transformer coils with primary windings may be arranged in a common casing and connected in parallel.

What I claim and desire to secure by Letters Patent is:—

1. A single phase low tension transformer for welding, melting or like purposes, comprising a secondary winding in the form of a protective casing, a primary winding inclosed within said casing and a core integral 115 with said casing, said primary winding being interposed between said core and casing.

2. A single phase low tension transformer for the purpose specified, comprising, in combination, primary and secondary windings, the latter constituting a protective casing for the former which is inclosed therein, said casing being provided with a removable cover and a central core, each forming a part thereof. 120

3. A single phase low tension transformer for the purpose specified comprising a secondary winding in the form of a casing, 125

a central member forming part of said casing and a primary winding and core in said casing and around said central member.

5. 4. A single phase low tension transformer for the purpose specified comprising a secondary winding in the form of a casing a central member in said casing a removable and adjustable cover for said casing form-

ing part of the winding, and a primary 10 winding and core in said casing.

In testimony whereof I have affixed my signature in presence of two witnesses.

RICHARD MACK.
